SHOE TREE

Joseph W. Droll, Wilmette, Ill.

Application December 13, 1943, Serial No. 514,009

11 Claims. (Cl. 12—128.6)

The invention relates to shoe-trees.

One object of the invention is to provide a shoe-tree which comprises a fore member and a heel engaging member and a device which is adapted to expand the members to distend the shoe after the entire shoe-tree with the expanding device has been set into the shoe.

Another object of the invention is to provide a shoe-tree which comprises an adjusting device which compresses slidably overlapping stems and a collar by which the fore and heel members may be shifted for distending shoes of a wide range of lengths.

A further object of the invention is to provide a shoe-tree which is simple in operation, can be manufactured at a low cost, and efficient in distending shoes of different lengths.

Other objects of the invention will appear from the detail description.

The invention consists in the several novel features which are hereinafter set forth and more particularly defined by claims at the conclusion hereof.

In the drawing:

Fig. 1 is a longitudinal section of a shoe-tree exemplifying the invention.

Fig. 2 is a transverse section taken on line 2—2 of Fig. 1.

Fig. 3 is a perspective of the stem which is pivoted to the fore member of the shoe-tree.

Fig. 4 is a perspective of the heel member of the shoe-tree and the stem thereon.

Fig. 5 is a perspective of the fore member.

Fig. 6 is a sectional perspective of the collar for slidably shifting the stems on the members.

Fig. 7 is a perspective of a modified form of the fore member.

The invention is exemplified in a shoe-tree comprising a member 8 which is adapted to fit snugly into the heel portion of a shoe and is provided with a knob or handle 9 for convenience in placing the tree into and removing it from the shoe. The shoe-tree also comprises a fore member 10 which is adapted to fit into the toe and instep or arch portions of the shoe and on the sole of the shoe. The fore member 10 is provided with a recess 11 in its upper and rear portion and with ventilating slots 12.

The fore and heel members are connected for expansion to distend the shoe after the shoe-tree has been placed into the shoe, and contraction for removal of the tree from the shoe, by a stem 16 which is rigid with and extends longitudinally forward from the heel member which is pivotally connected by a transverse pin 14 to, and is housed

in, the recess 11 in the fore member 10, and a collar 18 which fits and is rotatable around both of the stems 16 and 17.

The stems 16 and 17 extend longitudinally through the collar 18, are semi-cylindrical in cross section, and have flat mating surfaces 23, 24, respectively. The stems 16 and 17 overlap each other between the fore and heel members and their flat faces engage each other for relative sliding movement. The collar 18 has a bore which extends longitudinally therethrough so that both of the overlapping stems can slide through the collar. The semi-cylindrical peripheral surface of the stem 17 is provided adjacent the head 13 with semi-circular or circumferentially sectional right-hand screw threads or helical ribs 20. The semi-cylindrical peripheral surface of stem 16 is provided adjacent the member 8 with semi-circular or circumferentially sectional left-hand screw threads or helical ribs 22. The front end of the bore of collar 18 is provided with a right-hand female screw thread 19 which engages the threads 20 on the front end of the stem 17. The rear end of the bore of collar 18 is provided with a left-hand screw thread 21 for engaging the threads 22 on stem 16. The semi-cylindrical surface of stem 17 which extends rearwardly from the threads 20, slidably fits the inner periphery of the thread 21 in the collar 18 to permit the rear portion of said stem to slide through the screw thread 21. The semi-cylindrical portion of the stem 16 which projects forwardly from its screw thread 22 slidably fits the inner periphery of the screw thread 19 to permit said stem to slide through said screw thread 19. In this construction the rearwardly slidable stems are held together in mating relation by the collar and the stems are slidable in opposite directions through and by rotation of the collar. The flat mating faces also prevent relative rotation of the stems in the collar. The free or rear end of stem 17 is adapted to slide into a semi-cylindrical socket 25 which conforms to the cross-sectional shape of said end of the stem and is formed in the heel member 8. The free or front end of stem 16 is adapted to slide into a semi-cylindrical socket 26 which conforms to the cross-sectional shape of said end of said stem and is formed in the head 13.

In this construction the overlapped and relatively slidable stems are supported by the heel and fore members and conjointly support the collar 18 for rotation around the overlapping stems and the stems are relatively slidable to expand and contract the members by rotation of the collar in opposite directions. This construc-

tion also provides for an extended range of adjustment between the members so that the shoe-tree will be adapted for distending shoes of substantially different lengths. The socket in heel member 8 and head 13 for the stems permit a substantial range of movement for this purpose. The outer periphery of collar 18 is preferably grooved or fluted as at 27 to provide a surface which can be easily gripped in rotating the collar.

The head 13 to which stem 17 is attached, forms a central and upper section of the fore member 10 and is provided with an arcuate bottom surface and the recess 12 in the member 10 is conformably curved to permit the heel member, head 13, stems 16 and 17 and the collar 18 to be conjointly and pivotally moved around pin 14 to facilitate the insertion of the member 10 by a direct forward movement into the shoe. This pivotal connection also facilitates the removal of the fore member from the shoe when the heel member 8 is slightly retracted.

In the use of the shoe-tree the collar 18 is rotated to bring the heel and fore members sufficiently close to permit the entire assembly to be inserted into the shoe. After the assembly has been placed in the shoe, the rotation of the collar 18 in one direction will slide the stems 15 and 17 and the members apart to distend the shoe to the desired extent. In this rotation of the collar 18 its right and left hand screw connections with the stems function to spread the members apart both for adjustment to permit the shoe-tree to be inserted into and removed from the shoe and to distend the shoe after such insertion, as well as to permit the members to be contracted sufficiently for the removal of the tree from the shoe.

In the modification illustrated in Fig. 7, the stem 17^a is rigid with or integrally formed with the fore member 10^a. This simplifies the device. The range of adjustment of the mating stems by the collar 18 is sufficient to permit the heel member to be adjusted sufficiently close to the fore member to permit the free insertion of the assembly forwardly and downwardly into the shoe and to spread the members apart by rotation of the collar after insertion.

The invention exemplifies a shoe-tree which is simple in construction and composed of relatively few parts. A single adjusting device, such as a collar, functions to slidably shift the overlapping stems both for distending shoes of different lengths and for the insertion of the tree into and its removal from the shoe. The stems may be attached or rigidly integrally formed to the heel and fore members. The construction lends itself to the formation of the parts of suitable plastic material for production at a low cost.

The invention is not to be understood as restricted to the details set forth, since these may be modified within the scope of the appended claims without departing from the spirit and scope of the invention.

Having thus described the invention, what I claim as new and desire to secure by Letters Patent is:

1. A shoe-tree comprising a fore member, a heel member, slidably overlapping stems, one of which is rigid with the heel member and the other of which is connected to the fore member, a collar encircling and rotatable around the overlapped stems, and means between the collar and both of the stems for longitudinally and slidably shifting the stems and adjusting the spacing between the members by rotation of the

collar after the members with their stems and the collar have been placed in the shoe.

2. A shoe-tree comprising a fore member, a heel member, slidably overlapping stems, one of which is rigid with the heel member and the other of which is pivotally connected to the fore member, a collar encircling and rotatable around the overlapped stems, and means between the collar and both of the stems for longitudinally and slidably shifting the stems and adjusting the spacing between the members by rotation of the collar after the members with their stems and the collar have been placed in the shoe.

3. A shoe-tree comprising a fore member, a heel member, slidably overlapping stems, one of which is rigid with the heel member and the other of which is rigid with the fore member, a collar encircling and rotatable around the overlapped stems, and means between the collar and both of the stems for longitudinally and slidably shifting the stems and adjusting the spacing between the members by rotation of the collar after the members with their stems and the collar have been placed in the shoe.

4. A shoe-tree comprising a fore member, a heel member, slidably overlapping stems, one of which is rigid with the one member and the other of which is connected to the other member, a collar encircling and rotatable around both stems and provided with a bore through which the free ends of both stems are slidable, and means between the collar and both stems for slidably shifting the stems and adjusting the spacing between the members by rotation of the collar after the members have been placed in the shoe.

5. A shoe-tree comprising a fore member, a heel member, slidably overlapping stems, one of which is rigid with the one member and the other of which is connected to the other member, a collar encircling and rotatable around both stems and provided with a bore through which both stems are free to slide, and means between the collar and both stems for slidably shifting the stems in opposite directions and adjusting the spacing between the members by rotation of the collar after the members have been placed in the shoe, the members being provided with sockets into which the opposite ends of the stems are adapted to slide.

6. A shoe-tree comprising a fore member, a heel member, slidably overlapping stems connected to the members, respectively, the stems being provided on oppositely disposed peripheral portions with circumferentially sectional screw threads of opposite trend, and a collar encircling the overlapped portions of the stems and provided with screw threads of opposite trend, and means on the stems engaged by the threads on the collar for longitudinally and slidably shifting the stems in opposite directions and adjusting the spacing between the members while they are in the shoe.

7. A shoe-tree comprising a fore member, a heel member, stems substantially semi-cylindrical in cross-section, having flat slidably engaging flat faces connected to the members, respectively, a collar encircling and rotatable around both stems, and means between oppositely disposed peripheral portions of the stems and the collar for longitudinally and slidably shifting the stems in opposite directions and adjusting the spacing between the members by rotation of the collar while the members are in the shoe.

8. A shoe-tree comprising a fore member, a heel member, stems substantially semi-cylindrical

in cross-section, having flat slidably engaging flat faces connected to the members, respectively, the stems being provided on oppositely disposed peripheral portions with circumferentially sectional screw threads of opposite trend, and a collar encircling and rotatable around both stems and provided with means for engaging the threads on both stems and longitudinally sliding the stems in opposite directions in the collar and adjusting the spacing between the members while they are in the shoe.

9. A shoe-tree comprising a fore member, a heel member, slidably overlapping stems connected to the members, respectively, each member being provided with a socket into which the stem on the other member is slidable, the stems being provided on oppositely disposed peripheral portions with circumferentially sectional screw threads of opposite trend, and a collar encircling and rotatable around the overlapped stems and provided with screw threads for engaging the threads on and slidably shifting the stems and adjusting the spacing between the members while they are in the shoe.

10. A shoe-tree comprising a fore member, a

25

heel member, slidably overlapping stems connected to the members, respectively, the stems being provided on oppositely disposed peripheral portions with circumferentially sectional screw

5 threads of opposite trend, and a collar encircling and rotatable around the overlapped stems and provided with screw threads for engaging the threads on both stems and longitudinally adjusting the members while they are in the shoe, the 10 stems being extended to pass entirely through the collar.

11. A shoe-tree comprising a fore member, a heel member, stems substantially semi-cylindrical in cross-section, having flat slidably engaging flat 15 faces connected to the members, respectively, a collar encircling and rotatable around both stems, and means between oppositely disposed peripheral portions of the stems and the collar for longitudinal and slidably shifting the stems in opposite directions and adjusting the spacing between the members by rotation of the collar while the members are in the shoe, the members being provided with sockets into which the stems are 20 slidable, respectively.
